UNITED STATES PATENT OFFICE

EDWARD J. RAYMOND, OF SEATTLE, WASHINGTON

MERCHANTISE DISPENSING APPARATUS

Application filed February 24, 1931. Serial No. 517,720.

This invention relates to merchandise dispensing apparatus, and has for its object the provision of inexpensively constructed devices including a cabinet adapted to retain article-holding magazines with simple mechanism most advantageous for delivering the merchandise, one at a time, from said magazines.

A further and particular object, the preferred embodiment herein illustrated being peculiarly designed to handle unwrapped candy merchandise of relatively rapid turnover quality, more especially of that character purchased and consumed by children, is the provision of highly attractive dispensing apparatus wherein the ultimate consumer is assured of a sanitary condition in that the individual products are afforded a dispensation direct from the factory packed magazines, rendering the same free from handling, both with respect to the children themselves and the store-keeper.

Further and more particularly objects and advantages, together with the foregoing, will become apparent in the course of the following detailed description and claims.

The invention consists in the novel construction of the dispensing devices, the magazine co-operating therewith, the method and arrangement in packing the same, and in the novel adaptation and combination of the several parts, as hereinafter described and claimed.

In the drawings,—

Figure 1 is a front elevation of a cabinet constructed in accord with the present invention and illustrating in dotted-line the disposition of the assembled magazines therewith.

Fig. 2 is a transverse vertical section to the same, taken on the broken line section 2—2 of Fig. 1.

Fig. 3 is a rear elevation of said assembled cabinet.

Fig. 4 is a detail horizontal section on the line 4—4 of Fig. 2, particularly illustrating the dispensing control shown in the preceding views.

Figs. 5 and 6 are detail horizontal sections

representing modified forms of the control lever.

Fig. 7 illustrates in end elevation, the method of packing the aforementioned magazines in a conventional type paper-box carton, a retaining strip therefor being broken away and the carton proper represented in transverse vertical section.

Fig. 8 is a horizontal section taken on line 8—8 of Fig. 7.

Fig. 9 is a view of the blank from which the cabinet is formed; and

Fig. 10 is a detail perspective representing the manner of assembling said blank to produce said cabinet.

In carrying out the invention, I preferably stamp from cardboard, metal, wood veneer or the like, a blank 11 of the general configuration represented in Fig. 9, said blank providing parallel longitudinal scorings 12, 13 separating said blank into a back board 14 and aliform sides 15, 16. Stamped from the upper portion of said back-board, moreover, and pivotally retained thereto on the line of scorings 17 at its lower edge, is a flap 18 providing laterally spaced apertures 19, said apertures being disposed in alignment with apertures 20 of a complementary flap 21, the latter however, having wings 22 cut from the aforesaid sides 15, 16 and serving to afford, through straddling slits 23 co-operating with a progressive reduction of radius in the arcs 24, a frictional engagement with respect to the sides 15, 16, with a resultant retention of the flap and the sides in approximate right angular dispositions to the back board.

Pivoted oppositely of said flaps 18, 21, below and relatively adjacent the latter, what is hereinafter termed a base board 25 is further stamped from said back board and provides side-supporting wings 26 slit similar to the flap 21, as at 27, for straddling engagement to respective arcs. Pivot scorings 28 of said base board are disposed in alignment with the lower edge of a feed slot 29.

Reverting more particularly to Figs. 1 to 6, said blank is assembled in the form represented and suitably attached, as by adhesion, staples, or the like, to a reinforcing mem-

ber 30, the latter having a slotted throat 31 disposed conjunctively with aperture 29 for feeding engagement of the discharged merchandise. 33 represents a receiving platform 5 therebelow.

In such assembly, the base-board 25 is preferably reinforced by a strip 34 juxtaposed therebelow and serving to pivotally support a lever, having an operating handle 36 projecting through the aforesaid feed slots, said handle controlling the merchandise dispensation through pivotal motivity of a pelecoidal configured body 37, the inner inverted quadrants of which respectively dislodge the lowermost of a plurality of superposed articles contained in magazines 38.

To such end, said magazines, of an elongated configuration, are conformed to have their lower ends open, being passed through 20 the aligned apertures 19, 20 of the flaps 18, 21 and supported in spaced dispositions above the base board 25 through angular corner feet 40 projecting downwardly at respective outer sides of the same.

25 41 represents sight openings in rear faces of the respective magazines, advantageous in affording a gauge of the contents therein and for re-aligning the merchandise into horizontal dispositions should one of the same become accidentally upturned in successive dispensations.

30 In Figs. 5 and 6, I represent modified forms of operating levers accommodating control by the store operator alone, as 37¹, or as might be desired, selectively either by the operator or the purchaser, 37².

35 With attention to Figs. 7 and 8, I represent the packing of the factory filled magazines illustrated in the preceding views, in which 40 a plurality of said magazines are laid in side by side relation, as many as may be desired, one layer above another, within a carton 43, strips of cardboard 45 or other like agency being inserted between oppositely disposed feet 40 to retain a tight pack of the product within the magazines.

45 In the use of the invention, as herein embodied, the assembled cabinet is inverted and the magazines, with the open end at the top, inserted upwardly to have respective feet 40 abut the base board 25, the arrangement of the flaps 18 and 21 allowing of a ready insertion of the same but frictionally resisting dislodgment due to the resulting crimping of the same over the magazine wall responsive to dis-alignment from horizontal. The invention is especially adapted to the dispensation of chocolate covered wafers of the character generally referred to as "penny chews" 55 wherein the purchaser obtains a free candy bar should the inner material of the wafer be other than of a pre-determined specified color.

60 In the normal sale of this merchandise, the purchaser has generally heretofore been given access to a box containing the same,

resulting in a handling of substantially the entire contents with an extremely unsanitary condition prevailing. In dispensing such article through the present invention, the true element of chance enters in that the purchaser is entirely unaware of the amount of candy previously sold or of what color the inner material might be, such having been heretofore frequently determined, due to a portion of the chocolate covering being scratched or rubbed off.

70 75 The invention and use of the same is believed clear from the foregoing. While I have herein illustrated and described a preferred embodiment of the same, it is not my desire to confine myself except as by the limitations of the hereto annexed claims.

80 What I claim, is:—

- blank scorings, the sector formed in said wings being of a progressively decreasing radius which, in the assembling of said blank, is adapted for riding engagement in said 5 quadrant slots to yieldably retain said body portion, the lateral wings and the base board in their right angular relations, one to another.
4. In merchandise dispensing apparatus 10 having a cabinet formed from a polygonal material blank trisection by longitudinal scorings to separate the same into a central body portion and wings bordering sides of the same, said blank having longitudinally-spaced apertured flaps and a base board stamped through the body portion and interconnected therewith along one transverse edge of each, said flaps being bent outwardly into right angular relation to the body to dispose the apertures in longitudinal alignment, one flap aperture with another flap aperture, said base board being bent outwardly into right angular relation to the body to serve as a platform below said apertures, said 20 wings serving as legs to support said body portion in upright disposition responsive to bending of the wings at an angle to said body portion, an open-bottom merchandise-containing magazine arranged for slide reception through said aligned flap apertures, said magazine having means for supporting the open-bottom thereof in spaced disposition above the platform, and a lever pivoted to said platform and arranged for movement therebetween and the magazine bottom for successively ejecting the lowermost article in said magazine.
5. A supporting cabinet formed from a polygonal material blank trisection by longitudinal scorings to separate the same into a central body portion and wings bordering sides of the same, said blank having longitudinally-spaced apertured flaps connected with the body portion along the lower transverse edges of each and a base board stamped through the body portion and connected therewith along the upper transverse edge of the same, said flaps being bent outwardly into right angular relation to the body to dispose the apertures in longitudinal alignment, one flap aperture with another flap aperture, said base board being bent outwardly into right angular relation to the body to serve as a platform below said apertures, said wings serving as legs to support said body portion in upright disposition responsive to a folding of the same outwardly at an angle to said body portion, the object supported being adapted for slide reception through aligned apertures into seating engagement to said platform, said connection of the flaps along lower transverse edges expediting admission of the object through the apertures thereof, while resisting retraction from the same.
6. A cabinet formed from a material blank 65 trisection by parallel scorings to separate the same into a central body portion and wings bordering the same, said blank having a flap stamped through the body portion and a portion of the wings and connected to the body portion along one transverse edge, the lateral edges of said flaps projecting into the wings being arcuate and having re-entrant slots cut into the same in the plane of the blank scorings, the radii of said arc progressively decreasing from the point of the flap to accommodate a wedge action between said slot and the sector formed in the wings responsive to a bending of said flap and the wings at angles to the body portion and one to another.
7. In merchandise dispensing apparatus, a cabinet formed from a material blank trisection by scorings to separate the same into a central body portion and side wings, said blank having spaced-apart apertured flaps and a base board stamped through the body portion and connected therewith along one transverse edge of each, said flaps being bent outwardly into approximate right angular relation to the body to dispose the apertures of the flaps in alignment, said base board being bent outwardly into approximate right angular relation to the body to serve as a platform, a merchandise-holding magazine received through the apertures of said flaps, and ejection mechanism supported on said platform to successively deliver the articles from said magazine.
8. In merchandise dispensing apparatus, a cabinet formed from a material blank trisection by scorings to separate the same into a body portion and wing elements adapted to be bent at an angle to the body portion for supporting said body portion in an upright position, said blank having an apertured flap adapted to be bent at an angle to the body portion stamped from the body portion and connected therewith along one transverse edge, a merchandise-holding magazine engageable through the aperture of said flap for supporting the magazine, and ejection mechanism for delivering articles from said magazine carried by said cabinet.
9. The combination with a cabinet providing a floor, of a pair of open-bottom merchandise-containing magazines detachably supported by said cabinet to locate said bottom openings in spaced dispositions above the floor, and a lever member having an approximate pelecoidal configuration pivotally supported over said floor for movement in the space between said magazines and the floor, said pelecoid configuration providing quadrant-shaped members at each side of its pivot adapted to eject the lowermost article from a respective magazine with the body proper of the same acting to maintain the articles succeeding the ejected article in an elevated disposition during the period of article ejection.

EDWARD J. RAYMOND. 130
